UNITED STATES PATENT OFFICE.

ISAAC F. RUBEL, OF CHICAGO, ILLINOIS.

DESIGN FOR A KNIFE-HANDLE.

SPECIFICATION forming part of Design No. 16,741, dated June 15, 1886.

Application filed March 22, 1886. Serial No. 196,128. Term of patent 3½ years.

To all whom it may concern:

Be it known that I, ISAAC F. RUBEL, a citizen of the United States, residing at Chicago, in the county of Cook and State of Illinois, have invented and produced a certain new and original Design for Knife-Handles, of which the following is a specification, reference being had to the accompanying drawing, forming a part thereof, said drawing being a side view of a knife whose handle contains my said new and original design.

My design relates to the ornamentation of a knife-handle, and is distinguished by certain figures which appear upon the bolster and tip.

15 A is the scale or side plate. B is the bolster. C is the tip. Upon the bolster and tip appear the figures A' A'', shaped like ax-blades laid head toward head at a short interval. The narrow band of surface of the bolster or tip, showing between the opposed heads of the ax-blades, causes the entire appearance to re-

semble an ancient battle-ax or double-bitted ax, the said intervening band appearing as the thong or rawhide or bent-wood strip by which the handle was secured to the neck of the ax between its two blades.

I claim—

The design for a knife-handle herein described and shown, containing the figure of a double-bitted or battle ax on the bolster and tip, made up of the two figures, each shaped as an ax-blade and placed head toward head, and an intervening band representing the thong.

In testimony whereof I have hereunto set my hand, in the presence of two witnesses, at Chicago, Illinois.

ISAAC F. RUBEL.
